UNITED STATES PATENT OFFICE

91,444

DESIGN FOR AN AIRPLANE

Thomas M. Shelton, Denver, Colo., assignor to
American Gyro Co., a corporation of Colorado

Application October 20, 1933. Serial No. 49,521

Term of patent 14 years

To all whom it may concern:

Be it known that I, THOMAS M. SHELTON, a citizen of the United States of America, residing at Denver, in the county of Denver and State of Colorado, have invented a new, original, and ornamental Design for Airplanes, of which the following is a specification, reference being had to the accompanying drawing, forming part hereof.

Fig. 1 is perspective view illustrating my new design.

Fig. 2 is a front elevation thereof.

I claim:

The ornamental design for an airplane as shown.

THOMAS M. SHELTON.
